Patented Dec. 21, 1915.

UNITED STATES PATENT OFFICE.

CLIFFORD TOON, SR., OF CHRISTCHURCH, NEW ZEALAND.

MEANS FOR USE IN CALKING LEAD JOINTS IN IRON PIPES AND MAINS.

1,165,041.

Specification of Letters Patent. Patented Dec. 21, 1915.

Application filed August 26, 1913. Serial No. 786,645.

To all whom it may concern:

Be it known that I, CLIFFORD TOON, Sr., a subject of the King of Great Britain, residing at Public Trust Building, Cathedral

5 Square, Christchurch, New Zealand, have invented new and useful Improvements in Means for Use in Calking Lead Joints in Iron Pipes and Mains, of which the following is a specification.

10 This invention relates to means for use in calking the lead joints employed in connecting iron pipes used as mains for conveying gas, water, sewage and the like and refers more particularly to the calking of 15 joints formed with sponge lead. The invention is also applicable for use in any case where a joint is to be made by ramming in metallic packing.

Hitherto the practice has been to perform 20 the calking by hand for which purpose a suitable tool driven by a hammer has been applied successively at various points around the circumference until the joint has become sufficiently tight to prevent leakage. This 25 method however entails a considerable expenditure of time and requires great care in order to produce a joint that will be tight and satisfactory, while owing to the necessity of providing room for the hammer and 30 calking tool to be used upon the underside portion of the joint, a considerable amount of earth requires to be excavated at the point at which the operation occurs.

It is the object of the present invention 35 to provide means whereby the joint will be calked simultaneously at all points around the circumference of the pipe thus effecting a considerable saving of time while at the same time insuring regularity of the work. 40 The invention moreover necessitates very little clearance in which to work beneath the pipe thus avoiding to a great extent the excavation beneath the ordinary level of the bottom of the trench.

45 In order that the nature of the invention may be fully understood, reference will now be made to the accompanying sheet of drawings in which:—

Figure 1.— is an elevation showing the 50 device in place and portions of two pipes in readiness for jointing. Fig. 2.— is a longitudinal section of Fig. 1 along the line A—B. Fig. 3.— is a cross section of Fig. 1 along the line C—D. Fig. 4.— shows in 55 outline the two members of the tool hingeably connected together. Fig. 5.— is an

end view of the device as viewed from the operative end of the tool, and Fig. 6.— is a side elevation showing in outline an alternative formation of the tool for that of 60 Fig. 1.

Before describing the construction and operation of the invention it will be explained that the joint is prepared in the usual manner by placing the end of a pipe 65 1 within a socket 2 upon one end of the other pipe 3 and then placing lead 4 either in cast or sponge form so as to fill the annular space or interval 5 between the periphery of the end portion of the pipe 1 70 and the inner circumference of the socket 2, as clearly illustrated in Fig. 2.

The invention comprises a pair of semi-circular shaped calking tools 6 which are adapted to be placed together around the 75 pipe 1 so as to operate upon the adjacent end of the lead 4 at all points around the joint.

For the purpose of operating them simultaneously the said calking tools 6 are attached at their outer or reverse ends with a dolly or driver 7 which is slidable longitudinally upon the pipe 1. The said dolly 7 consists of a ring or member of the desired weight and adapted to encircle the 80 pipe 1, such member being preferably formed in two halves adapted to be secured together to enable the device to be conveniently placed in position or removed from the pipe. This securing together of the two 85 portions of the dolly may be effected in any convenient manner; as for instance, by means of bolts 8 passing through lugs 9 formed upon the two half portions of the dolly, as shown in Figs. 1, 2, 3, and 5 or 90 again the two portions may be connected at one side by means of a hinge 10, as shown in Fig. 4, any suitable means being employed to secure the two halves together 95 at the opposite side.

According to the drawings, in order to enable them to be attached to the dolly 7, the tools 6 are each formed at their outer or reverse ends with an out-turned flange 11 adapted to abut with the side face of the 100 dolly 7 in which position they are secured by means of bolts 12 passing through both the dolly 7 and flanges 6. In order to permit of slight adjustments of the total diameter of the tools 6 to accommodate the device 105 to such variations as may occur in the diameter of the pipes, the holes 13 in the

flanges, through which the bolts 12 pass, are somewhat slotted or elongated in a direction at right angles to the direction of diametrical division of the tool (as shown 5 in Figs. 2 and 5).

It must be understood however that the invention is not to be limited to such method of attaching the tool to the dolly as any other convenient means, either with or without provision for diametrical adjustment, 10 may be substituted, or in lieu thereof such tool may be formed integral with the dolly.

The forward end of the tool 6 which comes in contact with and operates upon the lead 15 may be square as shown in Fig. 1, so as to act upon the whole of the lead around the joint at each blow, or if thought desirable however, in order to reduce the surface against which the blow acts, the operative end of the 20 tool 6 may be toothed as indicated in Fig. 6, or otherwise formed to attain this purpose. In operating a tool of the latter description it will be necessary to turn the device occasionally upon the pipe through a sufficient 25 angle to enable the whole of the lead around the joint to be rammed to the same degree.

To permit of the dolly 7 being reciprocated upon the pipe 1 with a minimum of friction such dolly may be provided with a 30 plurality of inwardly radiating runners 14 adapted to slide upon the periphery of the pipe, such runners being mounted slidably in the radial direction in recesses 15 formed in the dolly and screws 16 being provided to 35 enable the position of the runners to be adjusted to suit varying diameters of pipes or to compensate for wear.

In lieu of this construction however the runners 14 may be dispensed with or formed 40 integral with the dolly or the same purpose may be effected by the employment of ordinary anti-friction rollers either adjustable or otherwise.

In operation the device is grasped either

by the dolly or by suitable handles 17 at- 45 tached thereon and caused to reciprocate upon the pipe 1 in such a manner as to cause the forward or operative end of the tool to deliver a succession of blows to the adjacent edge of the lead 4 around the joint which 50 process is continued until such joint has become sufficiently compact to produce a tight and satisfactory joint.

I claim—

1. A device for packing pipe joints comprising an axially split band adapted to be fitted slidably upon a pipe, means for securing the meeting edges of the band together, a weighted dolly of sectional construction adapted to be fitted slidably upon 60 a pipe and to bear against one end of the said band, means for securing the sections together, an annular flange provided upon the band and having radially elongated slots 65 therein, connecting bolt members extending through the dolly sections and the flange slots of the band, and means by which the dolly may be reciprocated.

2. A device for packing pipe joints comprising a band adapted to be fitted slidably 70 upon a pipe, an annular weighted dolly adapted to be fitted slidably upon a pipe and to bear against one end of the said band, means for securing the dolly to the band, means by which the dolly may be recipro- 75 cated, a plurality of relatively spaced runners mounted movably within the dolly for engagement with a pipe extending there- 80 through, and means connecting the runners with the dolly for adjusting the former radi- ally therein.

In testimony whereof I have signed my name to this specification in the presence of two subscribing witnesses.

CLIFFORD TOON, SENR.
